The ornamental design for a cap for packaging container, as shown and described.

DESCRIPTION

FIG. 1 is a front view of a first embodiment of a cap for packaging container showing our new design;

FIG. 2 is a right side view thereof;

FIG. 3 is a top side view thereof;

FIG. 4 is a bottom plan view thereof;

FIG. 5 is a sectional view thereof taken on line 5-5 of FIG. 1;

FIG. 6 is a perspective view thereof;

FIG. 7 is a reference view thereof showing a condition in use;

FIG. 8 is a front view of a second embodiment of a cap for packaging container showing our new design;

FIG. 9 is a right side view thereof;

FIG. 10 is a top side view thereof;

FIG. 11 is a bottom plan view thereof;

FIG. 12 is a sectional view thereof taken on line 12-12 of FIG. 8;

FIG. 13 is a perspective view thereof;

FIG. 14 is a reference view thereof showing a condition in use;

FIG. 15 is a front view of a third embodiment of a cap for packaging container showing our new design;

FIG. 16 is a right side view thereof;

FIG. 17 is a top side view thereof;

FIG. 18 is a bottom plan view thereof;

FIG. 19 is a sectional view thereof taken on line 19-19 of FIG. 15;

FIG. 20 is a perspective view thereof; and,

FIG. 21 is a reference view thereof showing a condition in use.

In each of three embodiments, a rear view and a left side view are omitted because the rear view is identical to the front view and the left side view is identical to the right side view.

The broken line showings of FIGS. 7, 14, and 21 are environmental only and not part of the claimed design.
